CARTRIDGE BELT LINK

John J. Murphy, Oakville, Conn., assignor to
 The Autoyre Company, Incorporated, Oakville,
 Conn., a corporation of Connecticut

Application July 14, 1945, Serial No. 605,079

3 Claims. (Cl. 89—35)

1

This invention relates to metallic cartridge belt links, more particularly to metallic cartridge belt links which are interlinked and hinged together by the cartridges received in the links to form a belt of ammunition and it is an object of the invention to provide an improved cartridge belt link of the character indicated.

The universal character of the movements of a rapid fire gun during operation from both relatively fixed and rapidly moving gun mounts and the necessity for an ammunition belt having the required attributes of flexibility in order to satisfactorily operate in the gun are well recognized. Likewise, it is known that the limitations of space around a gun are such that ammunition belts must be stored in awkward but relatively accessible places not always convenient to the gun, thereby making it necessary that the ammunition belt be capable of additional twists and turns. A cartridge belt link fulfilling the necessary requirements as to flexibility when assembled into an ammunition belt is described and claimed in a co-pending patent application Serial No. 469,679 filed December 21, 1942 in the name of Roy S. Sanford and entitled "Cartridge belt link," and issued on December 4, 1945 into Patent No. 2,390,331, which patent is assigned to the same assignee as the present invention. The cartridge belt link of the said Sanford application comprises two cartridge-receiving members connected by a universal joint which permits the cartridge-receiving members to move relative to each other as the ammunition belt twists and turns during use. With universal joints between the links holding the rounds of ammunition and because the rounds are mounted in the links substantially at their centers of gravity, the jerks and movements imparted to the ammunition belt by the short jerking movements of the gun feeding mechanism and the additional jerking movements caused by rapidly moving the gun from one position to another, may give rise to a tendency for the rounds to flop indiscriminately from one position to another out of line and to remain out of line. Accordingly, it is a further object of the invention to provide an improved cartridge belt link of the character indicated having a restrained swivel or joint by virtue of which the relative movement between the members of the link brings into operation a force tending to restrain the relative movement.

It is a further object of the invention to provide an improved cartridge belt link of the character indicated in which a force is brought into operation by the relative movement of the link

2

members from a normal position to return the link members to a normal position relative to each other after displacement therefrom.

Ammunition belts having a large number of rounds are heavy and consequently the feeding mechanism of a gun must exert a strong pull to feed the ammunition. The ammunition in its pathway to the gun passes around feed and guide rollers and through guide chutes which necessitate that the rounds twist and turn to some degree, and it is apparent that such twists and turns must be made with as little resistance as possible in order not to increase unduly the load on the gun feeding mechanism. Accordingly, it is a further object of the invention to provide an improved cartridge belt link of the character indicated in which the force restraining the movement of the members of the link relative to each other is initially small and increases as the amount of the relative movement increases.

The sharp quick jerks of the gun feeding mechanism are imparted to the whole ammunition belt and consequently accelerate the ammunition belt with the same short jerking movement. This not only places a heavy shock or acceleration load on the gun feeding mechanism, but it places a heavy strain on the cartridge belt links immediately adjacent the gun which bear the total force exerted in moving the ammunition belt. Accordingly, it is a further object of the invention to provide an improved cartridge belt link of the character indicated in which there is relative movement between the link members in the direction of feeding and the relative movement is resiliently restrained so as to provide a shock absorbing effect.

In carrying out the invention in one form, a cartridge belt link is provided having two cartridge-receiving members which are joined to each other with a universal joint and have a normal position and a limited degree of movement relative to each other. One of the cartridge-receiving members comprises a pair of axially spaced cartridge-receiving elements with an integral bridging member connecting the elements, the bridging member including a centrally disposed aperture and a pair of spaced guides defining the edges of the aperture. The second cartridge-receiving member comprises a resilient single cartridge-receiving element having a pair of tongues extending therefrom through the centrally disposed aperture and terminating in a pair of laterally projecting lugs which engage the bridging member to connect the two members of the links. The pair of tongues extend angu-

larly outward from their junction with the single cartridge-receiving element and are biased into contact with the guides or edges of the aperture by virtue of the resilience of the single element. The tongues are so formed that rotation of the single element to cause its axis to rotate in a plane perpendicular to the plane of the axes of all the link members causes the tongues to move into a position where there is only one point of contact of each tongue with a corresponding guide, and consequently a force becomes effective to prevent rotation of the single element from its normal position and to return it to its normal position after rotation. By virtue of the tongues extending angularly outward, the guides or edges of the aperture are received between the junction of the tongues and the single element where the tongues are closest together. Rotating the single element so that its axis rotates in a plane containing all of the axes of the link members causes the tongues to move closer to each other and causes the guides to slip along the angular extent of the tongues, thereby creating a force tending to resist this rotative movement of the single element and to return the single element to its normal position after movement.

In a specific embodiment of the invention, the guides or edges of the aperture are curved concave toward each other and the tongues are flat to provide only a two-point contact in the normal position and are movable to a one-point contact when the single element is moved relative to the other member of the link, whereby the single element returns to its normal position after displacement therefrom by virtue of the fact that the tongues seek the point of maximum distance apart which is the center of the aperture.

For a more complete understanding of the invention, reference should now be had to the accompanying drawings, in which:

Fig. 1 is a top plan view of one member of a cartridge belt link embodying the invention;

Fig. 2 is a top plan view of another member of a cartridge belt link embodying the invention;

Fig. 3 is a side elevational view partly in section of an assembled link embodying the invention;

Fig. 4 is an end elevational view partly in section of a link in assembled and unassembled condition;

Fig. 5 is an enlarged fragmentary top plan view of the assembled link showing one aspect of operation;

Fig. 6 is an enlarged fragmentary view taken substantially along line 6-6 of Fig. 3;

Fig. 7 is a view similar to the view of Fig. 6 showing another aspect of the link operation, and

Fig. 8 is a side elevational view, partially in section, of Fig. 7.

Referring more particularly to the drawings, the invention is embodied in a cartridge link 10 comprising two cartridge-receiving members 11 and 12 connected together and adapted to receive adjacent cartridges. In a belt for holding a number of cartridges successive links each having substantially identical members 11 and 12 are assembled together with the cartridges in a well known manner.

The cartridge-receiving member 11 comprises a pair of cartridge-receiving loops or elements 13 and 14 which are spaced from each other along the axis of the cartridge so as to provide a space to receive the member 12 of an adjacent link. Integrally attached at one side thereof to each of the elements 13 and 14 and extending between

them is a bridging member 15 for engaging the member 12 to complete the link, the link 12 having suitable connecting means extending through an aperture 23 in the bridging member. The bridging member 15 is essentially dish-shaped or U-shaped in both its longitudinal and transverse dimensions as is most clearly shown in Fig. 3, and has a base 16, upstanding flanges 17 and 18 extending along the sides of the base, and upturned portions 19 and 20 at the ends of the base which are joined to the elements 13 and 14 respectively. With this construction the base 16 of the bridging member 15 is spaced from the center surfaces of the elements 13 and 14, leaving a clearance between the base 16 and the cartridge received by the elements, thereby affording a space in which the connecting elements of the member 12 are received without coming into contact with the cartridge. Furthermore, the flanges 17 and 18 make the bridging member 15 a rigid structure and add additional strength to it, and to further increase the rigidity of the structure the embossments 21 and 22 are formed in the end portions 19 and 20, the embossments extending into and disappearing into the surfaces of the elements 13 and 14 respectively, as shown best in Figs. 1 and 4. The relatively great strength and rigidity of the bridging member is necessitated by the fact that the aperture 23 leaves a relatively small amount of metal in the cross section of the bridging member which is required to carry the relatively heavy load in a full belt of cartridges.

The aperture 23 is centrally disposed in the base 16 of the bridging member between the flanges 17 and 18 and the end portions 19 and 20, and is formed to provide suitable guides or edges 24 and 25 adjacent the flanges 17 and 18 respectively, which guides are curved as shown. The guides or edges 24 and 25 are substantially circular and have a radius substantially greater than the radial distance from the center of the aperture. Extending inwardly of the aperture from the ends of the bridging member adjacent the upturned end portions 19 and 20, and disposed centrally between the curved edges or guides 24 and 25, are the bosses or projections 26, the bosses and the curved edges defining recesses 27.

The cartridge-receiving element 14 which receives the large diameter of the cartridge is substantially circular in shape and is adapted to firmly grip the cartridge so that the cartridge will not fall or slide out of the link. For this purpose the element 14 is resiliently formed and its inside diameter is somewhat smaller than the outside diameter of the cartridge so that the element is forced to expand when a cartridge is inserted, and to provide for this expansion the element 14 is split as shown. The end portions of the element 14 are provided as described in the said Sanford application with suitable hook shaped portions having the inwardly projecting fingers 28 and 29 which overlap each other and, therefore, interengage to prevent the element 14 from expanding beyond a permissible amount. Extending outwardly from the sides of the element 14 are embossments 32 and 33 forming flat surfaces for engagement by the feeding mechanism of the gun.

The element 13, which is adapted to receive the smaller diameter of a cartridge, is also substantially circular in form and is resilient so that it will firmly grip the inserted cartridge, the element being split as shown to permit expansion when the cartridge is inserted. One of the split ends is provided with a cutout portion 30

and the other end is provided with a tongue 31 fitting therewith, the ends tapering away from the cutout portion and the tongue. While the cross section of the element 13 may be of any desired shape, it is shown as being circular to facilitate the insertion of the cartridges.

The cartridge-receiving member 12 comprises a single split loop or element substantially circular in form and is somewhat larger in diameter than the diameter of the cartridge received thereby so that the loop may contract during certain of its functions and in order that the cartridge may fit loosely in the loop as shown by the broken line 9 in Fig. 4 to permit the links to pivot readily about the cartridges and facilitate bending around feed and guide rollers. Referring to Figs. 2 and 4, the loop 12 is seen to be in the form of a split ring having two parts 36 and 37 spaced apart by a slot 38 which extends substantially around the loop. The loop 12 is open at one side thereof providing two ends, each terminating in a narrow integrally formed tongue 34. The tongues 34 extend upwardly from the ends of the loop and terminate in the lugs 35 which extend laterally from the tongues, the lugs extending through the aperture 23 and serving to connect the element 12 to the bridging member 15 to join the link members together. The tongues 34 are substantially rectangular in cross section, thereby providing flat surfaces facing the curved edges 23 and 24 in the assembled condition, and are bent at an angle to the ends of the loop 12 to extend angularly outward from their junction therewith so that the outermost ends of the tongues from which the lugs 35 project are spaced a greater distance apart than the innermost ends of the tongues which join with the loop 12. At the junction of the tongues with the loop proper there are cutout portions 39 from which the tapering ends 40 of the loop parts 36 and 37 extend to the edges of loop, the cutout portions and the tapering edges providing for the desired degree of movement of the link parts relative to each other. The loop 12 is resilient and in the unassembled condition it is sprung outwardly as shown by the dotted outline of Fig. 4.

The cartridge-receiving members 11 and 12 are separately formed from flat metal stock by stamping a blank having the desired outline, bending or otherwise forming the blank into the desired shape followed by heat treating and finishing operations. The member 12 is assembled to the member 11 by compressing the loop 12 from the dotted position shown in Fig. 4, thereby pressing the tongues 34 and lugs 35 together and inserting the lugs and tongues through the aperture 23. Thereafter the loop is released and through its resilience it expands to the position shown in Fig. 6 and by the solid outlines of Fig. 4, in which position the tongues 34 at their junction with the loop 12 bear against the curved edges 24 and 25 and the lugs 35 are spaced upwardly from the base 16 of the bridging member. In the event that force is exerted tending to pull the members 11 and 12 apart, the tongues 34 are forced to move toward each other by virtue of their angular direction and the lugs come into contact with the base of the bridging member and effectively prevent the links from coming apart. An assembled ammunition belt consists of a number of links with their loops 12 placed between the elements 13 and 14 of adjacent links and cartridges inserted into the three loops in a row.

During use, the ammunition belts make numerous twists and turns thereby placing stresses in

the links and causing the various parts of the link to move relative to each other. It is highly desirable that there be as little resistance as possible to the movement of the link parts relative to each other during the twists and turns of the belt while it is being used, so that there will be no more than the minimum load placed on the feed mechanism arising out of the necessity of deforming the links to obtain the twists and turns of the belt. It is 5 equally desirable that there be some resistance to the movement of the link parts relative to each other to prevent the cartridges from indiscriminately flopping from one position to another due to random causes and that there be some means 10 to bring the cartridges back into a straight line 15 to bring the cartridges back into a straight line after displacement therefrom.

Referring to Fig. 5, the bridging member 15 of the member 11 and the lugs 35 of the loop member 12 are shown in two relative positions, 20 the normal position being shown by the solid outline of the lugs and the dotted outline of the lugs 35 indicating the position of the parts when the members 11 and 12 are turned relative to each other so that the axes of the two members are turned in planes which are perpendicular to the plane containing the axes of the two members 25 before turning. Since the edges 24 and 25 are curved and the tongues 34 are flat, in the normal position of the link members one of the tongues contacts the curved edge or guide 24 at two points 30 41 and 42, and the other of the tongues contacts the curved edge 25 at two points 43 and 44, the tongues being biased into the two-point contact by the spring action or resiliency of the loop 12. 35 When the two members of the link are turned to the position indicated by dotted lines, it is seen that each of the tongues has moved to a position where one tongue contacts the edge 24 at only one point 42a and the other tongue contacts the edge 25 at only one point 43a, the points 42 and 43 having moved along the curved edges to the 40 points 42a and 43a, with the result that the tongues have moved closer to each other, as shown, and thereby have increased the spring force exerted by the loop 12 tending to return the tongues to the normal position.

The movement of the tongues toward each other is made up of two components. The first of these arises out of the fact that the radius 50 from the center of the aperture 23 to the point 42 or 43 is less than the radius of the curved edges 24 and 25 as previously pointed out. Therefore the curved edges 24 and 25 lie inside of a circle, indicated by the arcs 45, having the center of the aperture as a center and the distance 55 to the point 42 or 43 as a radius. Consequently, when the tongues are rotated the edges of the tongues following the curved edges 24 and 25 are forced inwardly. After the edges of the 60 tongues have moved to the points 42a and 43a, the friction of the tongue edges against the curved edges causes the tongues to become relatively stationary and the tongues pivot about the points 42a and 43a as centers, thereby also 65 causing the tongues to move closer together and giving the second component of movement. The amount of movement of the tongues is limited by the fact that one edge of each tongue comes into contact with the bosses or projections 26. 70 Since the tongues are resiliently biased in the outward direction by the spring action of the loop 12 and the tongues bear against the curved edges or guides at only one point when in the rotated position, it is evident that there is a 75 component of force creating a torque which

tends to rotate the tongues and return them to the normal position, and if the force resisting the return is not too great, the tongues will completely return to the normal position. Furthermore, the edges 24 and 25 being curved, the resiliency of the loop 12 causes the tongues to seek their outermost position which occurs when the tongues are symmetrically arranged in the aperture 23 between the ends of the aperture with each tongue having a two-point contact with the corresponding curved edge, and thus the member 12 is also restrained from movement in directions along its axes.

Referring to Figs. 6, 7 and 8 illustrating the relationship of the elements of the link when the two cartridge-receiving members are turned relative to each other so that the axes of the two members are turned in a plane containing both of the axes, Fig. 6 shows the members in the normal position and Figs. 7 and 8 show the members in the turned position. In this type of turning, if a series of cartridges and the assembled links were lying on a flat surface, the bases of the cartridges or the noses thereof would be pointing toward the center of a circle.

Referring first to Fig. 6, it is seen that in the normal position of the members the base 16 of the bridging member 15 is in contact with the loop 12 substantially at the junction of the tongues 34 and the loop 12, the lugs 35 being spaced upwardly from the base 16. Referring to Fig. 8 (the turned position), it is seen that the point of intersection of one of the tapered ends 40 with the corresponding cutout portion 39 bears against the bottom surface of the base 16 at point 46, and the opposite edges of the lugs 35 bear against the top surface of the base 16. In this position the turning movement is complete and further turning is impossible. During this turning movement the member 12 pivots or fulcrums about points 47 which are the points where the outside surfaces of the tongues 34 contact the lower edge of the curved edges or guides 24 and 25. Fig. 7 is an end view of the structure shown in Fig. 8, showing the turning movement complete with the lower surface of the lugs 35 in contact with the upper surface of the bridge 16.

It will be apparent that when the member 12 is pivoted or turned about the pivot points 47, the front edge of the tongues remain in contact with the curved edges or guides 24 and 25, and hence by virtue of the fact that the tongues extend upwardly and outwardly at an angle, the tongues will be forced inwardly by an amount depending on the angle at which the tongues extend from the loop 12. This, as well as the amount of the movement, is seen from comparing Figs. 6 and 7. Since the tongues are resiliently biased outwardly, they tend to resist inward movement and because of such inward movement there is a greater force tending to move the tongues outward, the outward force having a component along the angular tongues which creates a torque urging the tongues into the normal position. That is, rotating the member 12 causes the base 16 to climb upon the angular edges of the tongues to a position of instability, and unless some force is exerted to cause it to remain there, it will return to the lowermost or stable position.

Closely allied with the turning movement described in connection with Figs. 6, 7 and 8 is a movement of the members of the link which may

be termed stretching, in that the members 11 and 12 move apart with their axes in the same plane. Considering Figs. 6 and 7, and assuming that there is no turning or twisting but that a downward force is exerted on the loop 12 while the bridging member 15 is stationary, the downward force will cause the loop 12, and consequently the tongues 34, to move downwardly to a position corresponding to the front edge view of the tongues in Fig. 7, and consequently the tongues are moved inwardly toward each other.

By virtue of the angularly extending tongues, the force tending to move the tongues outwardly has a component along the tongues tending to return them to the uppermost position shown in Fig. 6 where the lower surface of the bridging member touches the loop 12. The movement of the tongues relative to the bridging member 15 is thus resiliently resisted and permits the ammunition belt to elongate resiliently under the jerks of the gun feeding mechanism, etc., thereby preventing shocks to the gun and other equipment. In an actual operation, of course, there will be complex movements, but the total movements of the link members may be resolved into components which are the simple ones described and the foregoing explanations will apply.

While a particular embodiment has been shown, it will be understood, of course, that the invention is not limited thereto since many modifications may be made, and it is, therefore, contemplated by the appended claims to cover any such modifications as come within the true spirit and scope of the invention.

Having thus described the invention, what is claimed and desired to be secured by Letters Patent is:

1. A cartridge belt link comprising a first cartridge-receiving member and a second cartridge-receiving member having a normal position relative thereto and having a limited degree of movement relative thereto, said first cartridge-receiving member comprising a pair of axially spaced cartridge-receiving elements, a bridge member connecting said axially spaced cartridge-receiving elements having an aperture disposed between said elements, the edges of said aperture defining spaced curved guides, said second member comprising a resilient single cartridge-receiving element and a pair of tongues extending angularly from said single element through said aperture and having a pair of lugs extending laterally from said tongues for engaging said bridge to connect said first and second members, said tongues being biased into contact with said guides by said single resilient element and having substantially flat surfaces contacting said curved guides with a two-point contact, the radius of curvature of said guides being greater than the radius extending from the center of said aperture to said contact points, whereby said movement effects movement of said tongues into a single-point contact with said guides and thereby creates a component of force tending to return said tongues to said position of two-point contact.

2. A cartridge belt link comprising a first cartridge-receiving member and a second cartridge-receiving member having a normal position relative thereto and having a limited degree of movement relative to said normal position, said movement comprising rotation of the axes of said members in planes perpendicular to the plane normally containing the axes of said members, said first cartridge-receiving member comprising a pair of axially spaced cartridge-receiving elements, a

bridge member connecting said elements having an aperture disposed between said elements and curved spaced guides defining the edges of said aperture, said curved guides being concave toward each other, said second cartridge-receiving element comprising a resilient single cartridge-receiving element and a pair of tongues extending from said single element through said aperture and terminating in a pair of lugs extending laterally from said tongues for engaging said bridging member to connect said first and second members, said tongues having substantially flat surfaces and being biased into two-point contact with said curved guides by said resilient single element, said guides having a radius of curvature greater than the radius extending from the center of the aperture to the contact points of the tongues with the guides and having an arcuate extent greater than the width of said tongues, whereby said rotation effects movement of said tongues into a single-point contact with said guides and thereby creates a component of force to return said tongues to said position of two-point contact.

3. A cartridge belt link comprising a first cartridge-receiving part, and a second cartridge-receiving part, one of said parts including aper-

ture means having opposed outer curved edges and the other of said parts including a pair of flat longitudinally disposed tongues extending therefrom at least one of which is resiliently formed, each of said pair of tongues terminating in an outwardly projecting lug, said tongues extending through said aperture means whereby said lugs engage said one part adjacent said curved edges for holding said parts together and the edges of said flat tongues engage said curved edges for resiliently restraining relative twisting movement of said parts.
